The ornamental design for a lottery poker game, as shown and described.

DESCRIPTION

FIG. 1 is a top plan view of the lottery poker game showing my new design;

FIG. 2 is a rear elevational view thereof;

FIG. 3 is a side elevational view thereof, the side opposite being a mirror image of the side shown in FIG. 3; and,

FIG. 4 is a top edge view thereof, the bottom edge view being identical to the top shown in FIG. 4.

FIG. 1

FIG.2

FIG. 3

FIG. 4
